UNITED STATES PATENT OFFICE.

PETER E. KROEHLER, OF NAPERVILLE, ILLINOIS.

SPRING CONSTRUCTION FOR UPHOLSTERED DAVENPORTS, COUCHES, AND CHAIRS.

1,122,283.

Specification of Letters Patent. Patented Dec. 29, 1914.

Application filed June 3, 1912. Serial No. 701,223.

To all whom it may concern:

Be it known that I, PETER E. KROEHLER, a citizen of the United States, and a resident of the city of Naperville, in the county of 5 Dupage and State of Illinois, have invented certain new and useful Improvements in Spring Constructions for Upholstered Davenports, Couches, and Chairs; and I do hereby declare that the following is a full, clear, 10 and exact description of the same, reference being had to the accompanying drawings, and to the numbers of reference marked thereon, which form a part of this specification.

15 Upholstered davenports, couches and chairs have usually, heretofore, been constructed either of a metal fabric secured practically at the top of the bottom frame, or have been constructed with comparatively 20 deep spiral (or other) springs, the lower ends of which are supported usually upon webbing or slats fastened at the bottom of the side and end frame members. In the former construction insufficient resiliency results; in the latter, insufficient durability, 25 and the occupation by the springs of practically the entire space within the bottom frame has been deemed necessary.

The object of this invention is to afford a 30 construction wherein the desired resiliency may be obtained and also great strength and durability, and in which the spring construction is supported wholly at or near the top of the frame.

35 It is an object of the invention to afford a construction wherein the stresses on the vertical springs are distributed laterally and longitudinally of the frame to suitable springs engaged to the frame.

40 It is an object of the invention also to afford an exceedingly resilient, though very shallow spring construction supported in the top of the frame, and occupying but slight space in the spring or upholstered 45 frame, thereby adapting the construction to be used for couches, davenports and the like, where room for storage beneath the spring structure is frequently an important object.

The invention (in a preferred form) is 50 shown in the drawings, and hereinafter more fully described.

In the drawings: Figure 1 is a bottom plan view, broken away, of a device embodying my invention. Fig. 2 is an enlarged, 55 fragmentary, transverse section thereof. Fig. 3 is a similar view, slightly modified.

As shown in the drawings: 1, indicates the side frame members, and 2, the end frame members of the couch or davenport seat, which, as shown, is constructed of wood of suitable width and thickness, but, of course, 60 may be constructed of any suitable material. An angle bar spring frame is secured within said main frame, comprising integrally connected side and end members engaged in place within said frame by means of screws, bolts or otherwise, engaging through the downwardly turned flange thereof, and the inwardly projecting web of said angle bar frame is provided with apertures arranged 65 suitable distances apart at opposite sides and opposite ends of the frame. Engaged in each of said apertures in said side and end frame members 3 and 4, are strong, coiled springs 5, which are connected in 70 pairs transversely and longitudinally of the frame under tension by means of transverse wires 6, and longitudinal wires 7, respectively, as shown in Fig. 1. Threaded and seated upon the wires 6 and 7, at their intersections, are short, downwardly diminishing 75 spiral bed or upholstery springs, the lower ends of which are engaged in unvarying relation relatively to each other on said wires.

Secured to the side and end members 1 and 2, of the main frame, and around the top thereof, is a strong canvas covering 9, as shown in Figs. 2 and 3, which is drawn with sufficient tension over the upper or 80 larger ends of the upholstery spring to exert considerable stress thereon, and also on the springs 5. The padding or upholstery 85 10, and covering fabric 11, are placed thereon in any suitable manner, and engaged 90 around the margins of the main frame by suitable upholstery tacks 12, or other suitable means.

In the construction illustrated in Fig. 3, instead of an angle bar interior frame, a 140 bracing strip 14, of wood or other suitable material affording an inner frame, may be provided around the top of the main frame to strengthen and reinforce the same against the draft of the springs thereon.

The operation is obvious from the construction described. Downward pressure applied on the upholstery or cushion, serves to depress the coiled bed or upholstery spring, and the stresses applied thereon are directed, by means of the transverse and longitudinal wires 6 and 7, trans-

versely and longitudinally the frame to the coiled pulling springs 5, where such stresses are absorbed, thus affording an exceedingly soft and resilient construction, in exceedingly small compass as to thickness.

When used as the cover for a box couch, a davenport or otherwise, wherein it may be desired to store bedding within or partly within the main frame, a large storage space 10 is provided for that purpose. Of course, the ends of the rods or wires forming the various springs are either turned upwardly to avoid engaging in such fabrics as may be stored therein, as shown in Figs. 2 and 3, 15 or closed inwardly within the spring, to prevent engaging and tearing such fabric.

It is to be understood, of course, that I have shown but one embodiment of my invention, although numerous modifications 20 and variations in detail are possible. I therefore do not purpose limiting the patent granted on this application, otherwise than necessitated by the prior art.

I claim as my invention:

- 25 1. A device of the class described embracing a main frame, an angle bar frame secured therein and extending around the top thereof with the web turned inwardly and having apertures therein, transverse and 30 longitudinal flexible parallel members ar-

ranged within said frame and below the same, downwardly directed pulling springs connecting said members at their ends with said webs at said apertures and under tension, upholstery springs mounted at the 35 crossing points of said members acting to bind the same together to be supported thereon, and upholstery engaged around the margins of the main frame and drawn over said upholstery springs to tension the same 40 and the first described springs.

2. A device of the class described embracing a main frame, an angle bar frame secured therein and extending around the same with the web turned inwardly, transverse and longitudinal unconnected parallel 45 supporting wires arranged within said frame, pulling springs connecting said wires at their ends with said webs and under tension, and upholstery springs mounted at the 50 crossing points of said wires acting to bind the same together and supported thereon.

In testimony whereof I have hereunto subscribed by name in the presence of two subscribing witnesses.

PETER E. KROEHLER.
